UNITED STATES PATENT OFFICE

119,007

DESIGN FOR A DRESS

Bessie Recht, St. Louis, Mo., assignor to Dorsa
Dresses, Inc., St. Louis, Mo., a corporation of Missouri

Application December 15, 1939, Serial No. 88,921

Term of patent 3½ years

To all whom it may concern:

Be it known that I, Bessie Recht, a citizen of the United States and resident of the city of St. Louis, in the State of Missouri, have invented a new, original, and ornamental Design for a Dress, of which the following is a specification, reference being had to the accompanying drawing, forming part thereof.

I claim:

The ornamental design for a dress, as shown.

BESSIE RECHT.
